United States Patent Office

Des. 181,870
Patented Jan. 7, 1958

181,870

CHAIR

Vittorio Meneghelli, Germiston, Transvaal,
Union of South Africa

Application March 28, 1956, Serial No. 40,817

Term of patent 14 years

(Cl. D15—1)

FIG. 2.

Fig. 1 is a front perspective view of a chair showing my new design.

Fig. 2 is a side perspective view of the same.

The dominant features of the design reside in those portions shown in solid lines.

I claim:

The ornamental design for a chair, as shown and described.
